Inventor:

William Wilbarger,
By Frederick V. Winters,
Attorney.

UNITED STATES PATENT OFFICE.

WILLIAM WILBURGER, OF BROOKLYN, NEW YORK.

ALBUM FOR DISK RECORDS.

Application filed December 12, 1921. Serial No. 521,780.

To all whom it may concern:

Be it known that I, WILLIAM WILBURGER, a citizen of the United States, and resident of Brooklyn, in the county of Kings and State of New York, have invented certain new and useful Improvements in Albums for Disk Records, of which the following is a full, clear, and exact specification.

This invention relates to albums for disk records or other loose leaf books, and has for its object to provide improved and simplified means for detachably holding leaves in such books or albums.

Special objects are to support the leaves more evenly in the book, thereby insuring the ready movement thereof without danger of sticking or tearing, and to provide retaining members or bars of improved construction which will securely hold the leaves and may be easily applied and removed. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is a front elevation of an album constructed substantially in accordance with this invention, the front cover being swung to open position.

Figure 2 is a section on the line II—II of Figure 1 with the front cover closed, and

Figure 3 is a detailed perspective view of one of the retaining members.

The back 1 of the album or book may be made of wood, metal or composition and is formed substantially as illustrated in Figure 2 with a convex inner face 8, rounded edges 7, and inwardly extending ribs 5 spaced from said lateral edges 7. Said back 1 has a covering of cloth or other suitable material 3 on its outer surface which may be extended over the outer faces of the covers 2 of the book. A similar covering 4 is secured to the inner surface of the back 1 and may also extend around the ribs 5 and over the inner faces of the covers 2 of the book.

The ribs 5 have sockets 9 formed therein and opening on their outer faces 6 which

are preferably beveled inwardly to permit the covers 2 of the book to be fully closed without binding against said ribs. The leaves or record-holding envelopes 13 are 60 detachably fastened to the back 1 by arched retaining members or bars 11 having their middle portions curved to lie parallel to the convex inner face 8 of the back 1. The end portions 12 of the retaining members 11 are 65 bent to engage the outer faces of the ribs 5 and their extremities are bent inwardly substantially at right angles to said end portions 12 to enter the sockets 9, as clearly illustrated in Figure 2. Said retaining 70 members 11 are made of spring metal which is capable of holding the extremities 10 in the sockets 9 when engaged therewith. When it is desired to remove the leaves 13 from the book, or fasten others therein, one 75 end portion 12 of each retaining member may be forced or sprung outwardly to release its extremity 10 from the socket 9, whereupon the other extremity of each of said retaining members may be easily disengaged from its socket in the opposite rib 5. The retaining members being thus disengaged from the back 1, the leaves 13 may be easily removed or others added over either of the ends of said members. 85

The retaining members 11 are preferably made relatively broad and flat in order to provide adequate support for the leaves and at the same time offer minimum obstruction thereto. The leaves are provided with perforations 14 to loosely fit over the retaining members 11, and the inner edges 15 of said leaves are designed to rest against the covering 4 on the convex inner face of the back 1. Inasmuch as said inner face of the back 95 1 and the central portions of the retaining members 11 are parallel to each other, the engagement of said inner face of the back by the inner edges of the leaves or envelopes provides a much better support for said 100 leaves or envelopes than in prior constructions, there being no chance for the leaves to work in and out on the retaining members or bars which would tend to tear the perforations 14. 105

I claim:

1. The combination with a back having a convex inner face, of detachable leaf-retaining members having curved portions parallel to said inner face of the back for 110 the purpose specified.

2. The combination with a back having

2
a convex inner face, of detachable leaf-retaining members having curved portions parallel to said inner face of the back, and leaves having perforations for the passage 5 of said retaining members, the inner edges of said leaves engaging the convex inner face of the back, for the purpose specified.

3. The combination with a back having inwardly extending ribs arranged along the 10 surface of the same, said ribs having sockets in their outer faces, of arched leaf-retaining members having inwardly bent extremities to engage in said sockets for the purpose specified.

4. The combination with a back having inwardly extending ribs provided with sockets in their outer faces, the inner face of said back between said ribs being convex, of arched leaf-retaining members having 20 inwardly bent extremities to engage said sockets, the middle portions of said members being parallel to said convex inner face of the back for the purpose specified.

5. The combination with a back having inwardly extending ribs provided with sockets in their outer faces, the inner face of said back between said ribs being convex, of arched leaf-retaining members having inwardly bent extremities to engage said sockets, the middle portions of said members being parallel to said convex inner face of the back, and leaves having perforations for the passage of said retaining members, the 30

inner edges of said leaves engaging said convex inner face of the back for the purpose 35 specified.

6. The combination with a back having inwardly extending ribs provided with sockets in their outer faces, of arched leaf-retaining members having inwardly bent extremities to engage said sockets, the outer faces of said ribs being beveled inwardly 40 for the purpose specified.

7. The combination with a back having inwardly extending ribs, of leaf-retaining 45 members of spring material having bent ends to engage the outer faces of said ribs, and means for interlocking the extremities of said bent ends with said ribs, the resiliency of the members serving to normally 50 hold said extremities in interlocked engagement with said ribs.

8. The combination with a back having inwardly extending ribs provided with sockets in their outer faces, of leaf-retaining members, of spring material having bent 55 end portions to engage the outer faces of said ribs, the extremities of said end portions of said members being bent inwardly to enter said sockets in which they are normally retained by the resiliency of said members.

In testimony whereof I have signed my name to this specification.

WILLIAM WILBURGER.
